UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

GRIPPER MECHANISM.

Application filed April 12, 1928. Serial No. 101,314.

This invention relates to gripper mechanism.

One object of the invention is to provide gripper mechanism by means of which a sheet may be gripped with a substantially uniform pressure without nicety of gripper adjustment.

Another object is to provide gripper mechanism in which a fed sheet may be properly gripped without the necessity of giving the grippers the nicety of adjustment required when a solid pad is used.

Another object is to provide gripper mechanism in which there is no relative movement between the gripping surfaces of the gripper members after the sheet is engaged thereby, for the purpose of maintaining the proper position of the sheet or to prevent moving the engaged sheet out of register.

These and other objects are accomplished by means of the arrangement disclosed on the accompanying sheet of drawings, in which—

Figure 1 is a vertical sectional view of my improved gripper mechanism, including a plurality of gripper members and showing their relative positions with respect to a printing cylinder, and the means for supporting the gripper members, and

Figure 2 is a detail elevational view taken in the plane of line 2—2 of Figure 1.

The various novel features of the invention will be apparent from the following description and drawings, and will be particularly pointed out in the appended claims.

Referring to the figures of the drawings, it will be noted that I have disclosed my invention in connection with a printing press cylinder 10 in the gap of which there is mounted an operating shaft 11 and a supporting shaft 12. The gripper mechanism proper is mounted on said shafts within the cylinder gap adjacent one edge 13 of the sheet receiving surface 14 of the cylinder.

Heretofore, so far as applicant is aware, only solid gripper pads have been provided, and when referring to solid gripper pads such pads as rubber, felt, paper, as well as metal, are included. When solid gripper pads are used, it is necessary to make a very nice adjustment of the gripper fingers which are located at various points along the oper-

ating shaft so that said gripper fingers may press down upon the sheet with a uniform pressure. Such nicety of adjustment not only requires an expenditure of a great deal of time but is rather difficult to secure and maintain and also grip the sheet in a manner not to disturb its position on the cylinder. 55 My present invention contemplates overcoming the requirement of nicety of adjustment of the gripper fingers, and at the same time, the gripper mechanism is designed to grip a sheet with a uniform pressure and 60 without disturbing the position of the sheet on the cylinder. 65

One embodiment of the invention takes the form disclosed on the sheet of drawings wherein the gripper pad 15 is a pivotally mounted member, the pivot point 16 preferably being formed by a pin extending through the tail 17 of the gripper pad and through adjacent ears 18 formed on the bracket 19, which latter is adjustably secured to the supporting shaft 12. The bracket is provided with a recess 20 for the reception of a coiled spring 21 which engages the lower surface of the gripper pad and presses the gripper pad outwardly. 70 The outward pivotal movement of the gripper pad 15 is limited by engagement between the lower point of the tail 17 and an associated portion of the bracket 19. The gripper finger 22 is adjustably mounted on the 75 operating shaft 11. The pivotal points or centers 16 and 23 of the pad member 15 and the gripper finger 22 respectively are aligned with a point 24 on the gripping surfaces of said gripper members during the gripping action whereby said gripping surfaces have practically no relative movement after the sheet is engaged thereby, for the purpose of maintaining the proper position of the sheet, or in other words, to prevent moving the 80 sheet out of register. 85

From the arrangement described, it is apparent when the upper gripper member 22 presses down upon a sheet interposed between said upper gripper member 22 and the gripper pad 15, that if said upper gripper member 22 is given an excessive movement due, for example, to a rough adjustment of same on the shaft 11, such will be compensated for by the inward bodily pivotal movement of the gripper pad 15. At 95 100 105

the same time, the gripped sheet of paper will be gripped with substantially a uniform pressure throughout. An adjacent pair of gripper members may have a relative rough adjustment in which the gripper pad may be depressed a lesser or greater amount, the gripping pressure being substantially uniform. Thus it will be seen that if the various gripper fingers 22 distributed along the operating shaft 11 are given a relative rough adjustment as distinguished from a nice adjustment, the gripped sheet nevertheless will be gripped by the various gripper members with a substantially uniform gripping pressure. As mentioned hereinabove, the gripping surfaces of the gripper pad 15 and the gripper fingers 22 have practically no relative movement at the time a sheet is gripped, due to the pivotal arrangement of said gripper members. Therefore, the position of the gripped sheet is not changed, or in other words, does not have its register disturbed.

By means of the arrangement herein disclosed, the objects of the invention are accomplished. It is my intention to cover all modifications of the invention falling within the spirit and scope of the following claims.

30 I claim:

1. In gripper mechanism, the combination of a bodily movable gripper pad member, and a cooperating gripper member between which gripper members a sheet may be gripped, said gripper members being pivotally mounted on different relatively fixed centers in a manner whereby their gripping surfaces have practically no relative movement after the sheet is engaged thereby, to maintain the proper position of the sheet.

2. In gripper mechanism, the combination of a bodily movable gripper pad member, and a cooperating gripper member between which gripper members a sheet may be gripped, said gripper members being pivotally mounted on different centers which centers are aligned with a point on the gripping surfaces of said gripper members during gripping action whereby said gripping surfaces have practically no relative movement after the sheet is engaged thereby, to maintain the proper position of the sheet.

3. In gripper mechanism, the combination of a support, a pivotally mounted gripper

pad member carried by said support, and a cooperating gripper member mounted on a pivotal support fixed relative to the pivot of said gripper pad between which gripper members a sheet may be gripped, said gripper members being arranged in a manner whereby their gripping surfaces have practically no relative movement after the sheet is engaged thereby, to maintain the proper position of the sheet. 60 65

4. In a gripper mechanism, a plurality of supporting members, a pivotally mounted gripper pad member carried by one of said supporting members, and a gripper member pivotally mounted on another of said supporting members, said gripper pad member and gripper member being arranged in a manner whereby their gripping surfaces have practically no relative movement after the sheet is engaged thereby, to maintain 70 75 the proper position of the sheet.

5. In gripper mechanism, a support, a gripper pad member pivotally mounted on said support, a spring carried by said support and pressing said gripper pad member outwardly, means for limiting outward movement of said pad member, and a gripper member pivotally mounted on a separate support cooperating with said gripper pad member for gripping sheet material. 80 85

6. In gripper mechanism, the combination of a drum having an opening, gripping mechanism in said opening comprising a support having a recess therein, a gripper pad member pivotally mounted on said support, a spring mounted in said recess for moving said pad member in the gripping direction, means for limiting the outward movement of said gripper pad member, and a gripper member cooperating with said gripper pad member for gripping sheet material. 90 95

7. In gripper mechanism, the combination of a drum having an opening, gripping mechanism in said opening comprising a support having a recess therein, a gripper pad member pivotally mounted on said support, a spring mounted in said recess for moving said pad member in the gripping direction, and means for limiting movement of said gripper pad member. 100 105

Signed at Chicago, Illinois, this 9th day of April, 1926.

JOSEPH R. BLAINE.
